UNITED STATES PATENT OFFICE

163,364

LADY'S STOCKING

Vaughn Butler, Harriman, Tenn., assignor to Burlington Mills Corporation, Greensboro,
N. C., a corporation of Delaware

Application May 26, 1950, Serial No. 10,208

Term of patent 14 years

(Cl. D47—7)

To all whom it may concern:

Be it known that I, Vaughn Butler, a citizen of the United States and a resident of Harriman, in the county of Roane, State of Tennessee, have invented a new, original, and ornamental Design for a Lady's Stocking, of which the following is a specification, reference being had to the accompanying drawing, forming part thereof.

In the drawing, the single figure is a perspective view of a lady's stocking embodying my design.

I claim:

The ornamental design for a lady's stocking, as shown.

VAUGHN BUTLER.
